(57) **CLAIM**

The ornamental design for a fishbone tape, as shown and described.

DESCRIPTION

FIG. 1 is a top plan view of a fishbone tape, showing our new design;

FIG. 2 is a bottom plan view thereof;

FIG. 3 is a perspective view thereof; and,

FIG. 4 is a front view thereof, shown in use condition.

The fishbone tape in FIGS. 1-3 is shown with a symbolic break in its length. The broken lines in FIG. 4 represent unclaimed portions which are included for the purpose of illustrating unclaimed environment only, and form no part of the claimed design.
